UNITED STATES PATENT OFFICE.

MAX KREH, OF NEW ORLEANS, LOUISIANA, ASSIGNOR TO WICK NARROW FABRIC COMPANY, OF PHILADELPHIA, PENNSYLVANIA, A CORPORATION OF PENNSYLVANIA.

HATBAND.

Application filed January 13, 1927. Serial No. 160,841.

This invention relates to hat bands and with regard to its more specific features, to devices whereby such hat bands can be quickly and removably applied to hats.

5 In devices of this character it is important that the band should be adapted to fit hats of different sizes, should be capable of ready application to hats and subsequent removal therefrom without the use of any additional 10 implements or special skill, and that the method of application should not involve any stress upon the band or upon the bow usually associated with it, which might separate the two or injure them. It is of 15 equal or greater importance that the band and bow should have an attractive appearance; in particular that they should fit the hat snugly, be free from wrinkles, strains, frayed ends or other disfigurements and that 20 the point at which the hat band is overlapped or joined should be concealed from sight.

One difficulty which has been experienced in meeting these requirements lies in the fact 25 that when the bow is situated at one end of the band for the purpose of covering the point of overlapping or juncture, it becomes customary and even necessary for the person who would apply such a band to a hat or adjust the relation of the two, to grasp a portion 30 of the bow and pull vigorously upon it in order to make the band fit the hat firmly and prevent the band from wrinkling or accidental removal. This practice frequently 35 results in destroying the good appearance which is so much to be desired in bands of this character. For example, the tension upon the bow is likely to separate or loosen it from the band, and the grasp of the operator may also wrinkle and distort the shape 40 of the bow or cause the same to become soiled or frayed. The parts so damaged cannot be concealed but remain exposed to view after the attachment is complete.

45 The present invention seeks to overcome these difficulties and achieve the desirable results mentioned, in an efficient manner. It overcomes the necessity for grasping the bow or any other exposed part of the hat band, 50 by providing a concealed member which can be grasped instead for the purpose of applying the needed tension. It also localizes that tension in the body portion of the hat band so that no stress whatever comes upon the 55 bow nor upon the connection between the

bow and the hat band. It further provides a means for combining these advantages with devices whereby the band may be most readily attached to and disconnected from a hat. Thus my improved form of hat band 60 can be readily applied to or adjusted upon a hat by a person having no special experience or training, without the use of any tools and without any danger of damaging the structure or appearance of the hat band, its bow 65 or the connection between the two.

Other objects of this invention will be in part obvious and in part appear hereinafter.

The invention accordingly comprises an article of manufacture possessing the features, properties, and the relation of elements which will be exemplified in the article hereinafter described and the scope of the application of which will be indicated in the claim. 75

For a fuller understanding of the nature and objects of the invention reference should be had to the following detailed description taken in connection with the accompanying drawing, in which similar reference characters refer to similar parts; 80

Fig. 1 shows a perspective view of a hat band embodying my invention, the middle portion of said band being disposed in the position which it would occupy when encircling a hat. 85

Fig. 2 represents a top plan view of the end B of Fig. 1.

My hat band is constructed of fabric or other flexible material and has preferably 90 such length as will enable it to pass completely around the crown of a hat and permit the ends to overlap substantially. The body portion of the band is provided at its end A with means for attachment to the hat, 95 and for this purpose is folded back upon itself and fastened so as to form a sleeve to contain the rod a which has its two ends bent to form the hooks a', a'. These hooks project through the fabric and are so disposed that their points incline backward toward the center longitudinally of the hat band. The body portion of the band is provided at its end B with an ornament C 100 commonly called a bow, although, as shown, it is not a true bow knot and may vary in appearance, provided it serves the purposes set forth herein. This bow C is preferably 105 separate from the hat band, being merely fastened thereto by stitching or other con- 110

2
venient means as indicated in the drawings at *e e* and *f f*. The end *B* is also provided with a tab member *D* formed by an extension of the body portion of said band or otherwise integral therewith. In place of a tab, I may use a loop, hook, button or any other member attached to the body of the band, which can be readily grasped by the person applying the band. The end *B* 10 is also provided with attaching means such as the hooks *b', b'*, having the same construction as the hooks *a', a'*, and held in position by passing through holes in the band and being connected on the reverse 15 side by the rod *b*. The portion of the bow *C* which extends between the stitches *e e* and the stitches *f f* is preferably looped as shown, and is materially longer than the body portion of the band, which extends between 20 said points *e* and *f*, so that as a result any tension communicated to the body portion of the band by a pull upon the tab *D* will not create tension in any part of the bow *C* nor serve to distort nor injure it. 25 The end *c* of the bow *C*, which overlies the tab *D* is longer and preferably broader than said tab, and normally lies flat upon said tab so as to conceal it.

In use, the end *A* is placed against the 30 hat in the desired position and the hooks *a', a'* are pressed into the hat so as to become firmly affixed thereto. The remainder of the band is then disposed loosely about the hat with the bow *C* overlapping the end 35 *A*. The hooks *b', b'* will then be in position to engage said end *A*, but the band itself will be found somewhat wrinkled and lacking the snug fit and smoothness desired for good appearance. In order to obtain 40 this appearance, it is necessary that tension should be put upon the band until it is somewhat stretched and adheres closely to the hat. For this purpose the outer end *c* of the bow *C* is slightly lifted and the tab 45 *D* grasped by the user who is thus enabled to stretch the band as much as desired without any danger of soiling, wrinkling, or distorting the bow *C* or breaking the stitches by which it is connected to the body portion 50 of the hat band. After such tension has

caused the band to assume the desired condition, the hooks *b', b'* are forced through the overlapping portion of the end *A*, or the hat itself. The user then releases the tab *D* and permits the end *c* of the bow *C* to assume its normal position, as shown in Fig. 2, whereby it covers and conceals both the juncture of the band and the tab *D*. Thus the outward appearance of the band is not affected even though the tab should be wrinkled, soiled or damaged by its use. In case the band should become loose through wear, the user can adjust the band by grasping the tab *D*, pulling the hooks *b', b'* from the fabric, stretching the band until it fits the hat properly and then re-attaching the hooks *b', b'* as above described.

Since certain changes may be made in the above product and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which, as a matter of language, might be said to fall therebetween.

What I claim as new and desire to secure by Letters Patent is:

In combination, a band with free ends 85 adapted to encircle a hat crown and overlap each other, hooks adjacent one of said ends adapted for attachment to said hat, a second set of hooks adjacent the other end thereof adapted for engagement with an 90 overlapped portion of said band, a tab integral with said band and extending beyond said second hooks and adapted to be grasped for tightening said band prior to the said engagement of said second hooks, and a 95 separate bow affixed to said band and normally overlying said tab when said band is fully attached.

In testimony whereof I affix my signature.

MAX KREH.
